US00D808776S

(12) **United States Design Patent** (10) Patent No.: **US D808,776 S**
(45) Date of Patent: **** Jan. 30, 2018**

(54) **CABLE CONDUIT**

(71) Applicant: **D-Line (Europe) Limited**, Tyne and Wear (GB)

(72) Inventor: **Paul David Ruddick**, Tyne and Wear (GB)

(73) Assignee: **D-Line (Europe) Limited**, Tyne and Wear (GB)

(**) Term: **15 Years**

(21) Appl. No.: **29/605,544**

(22) Filed: **May 26, 2017**

Related U.S. Application Data

(62) Division of application No. 29/558,930, filed on Mar. 23, 2016, now Pat. No. Des. 790,477, which is a division of application No. 29/466,905, filed on Sep. 12, 2013, now Pat. No. Des. 754,612.

(57) **CLAIM**

The ornamental design for a cable conduit, as shown and described.

DESCRIPTION

FIG. 1 is a front perspective view of a cable conduit showing the claimed design;

FIG. 2 is a rear perspective view thereof;

FIG. 3 is a rear view thereof;

FIG. 4 is a front view thereof;

FIG. 5 is a right side view thereof;

FIG. 6 is a left side view thereof; and,

FIG. 7 is a top view thereof.

The shade lines in the drawings show contour and not surface ornamentation.

1 Claim, 2 Drawing Sheets
